BINDER SUPPORT FOR SEWING MACHINES

Frank A. Kucera, Chicago, Ill., assignor to Union
Special Machine Company, Chicago, Ill., a cor-
poration of Illinois

Application January 20, 1934, Serial No. 707,575

9 Claims. (Cl. 112—138)

The invention relates to new and useful improvements in a binder support for sewing machines. In the application of George Sauer, Serial No. 590,277, filed February 1, 1932, Patent Number 1,949,332, there is shown a binder support for a sewing machine of the type wherein the work support terminates and is spaced away from the standard, and the binder is mounted on the standard and supported so as to properly direct a binding strip about the edge of a fabric section passing over the work support. In this application there is also shown a means whereby the binder may be shifted from an operative to an inoperative position and locked in both of said set positions. The present invention is an improvement in the mounting for the binder disclosed in the application referred to, and has for an object to provide a binder support and locking means which permits the binder to be quickly withdrawn by grasping the latch which locks it in operative position and by a pressure on the latch in the same direction that releases the latch.

A further object of the invention is to provide a binder support of the above type wherein the binder when returned to operative position will be automatically locked in said operative position.

A still further object of the invention is to provide a support for the binder which includes means whereby said binder may be shifted toward and from the line of feed and also raised and lowered relative to the plane of the fabric for the proper positioning of the binder.

These and other objects will in part be obvious and will in part be hereinafter more fully disclosed.

Figure 1 is a front view of a machine embodying the improvements and showing in broken lines the binder moved to inoperative position;

Fig. 2 is a view partly in plan and partly in section taken just above the work support of the sewing machine;

Fig. 3 is an end view of the supporting bracket and the supporting means carried thereby on which the binder is mounted;

Fig. 4 is a horizontal sectional view centrally through the supporting means for the binder;

Fig. 5 is a sectional view on the line 5—5 of Fig. 2;

Fig. 6 is a perspective view of the supporting bracket for the binder, and

Fig. 7 is a view from the rear showing the manner of supporting the binder so that it may be

adjusted toward and from the edge of the fabric section which is being bound.

The sewing machine to which the binder is shown as applied includes a supporting bed 1 on which is mounted a standard 2 carrying a housing 3 in which is mounted the main actuating shaft driven from the belt wheel 4. Also mounted in this housing is the needle bar carrying a needle 5. The shaft is located in a line lying in a vertical plane which extends in the general direction of the line of feed and is inclined thereto. Cooperating with the needle beneath the work support is a looper mounted on a carrier 6 and operating in the usual manner. This type of machine to which the invention is shown applied is disclosed more fully in the patent granted Norman V. Christensen and Frederick F. Zeier, March 25, 1930, No. 1,751,508, and their application Serial No. 590,228, filed February 1, 1932, Patent No. 1,952,534.

Mounted on supporting members formed as a part of the bed 1 is a work support 7. The work support 7 terminates on a line located slightly to the right of the line of feed and the stitching point, as viewed in Fig. 1, and it extends to a suitable distance to the left thereof, thus forming a support for the fabric being stitched. Attached to the work support is a throat plate 8 which is raised above the upper face of the work support, and the fabric slides up on to and across the throat plate.

The throat plate is inclined at the front end thereof to aid in the directing of the fabric up on to the same. The fabric is held on the throat plate by a presser foot 9. Located at the right of the work support 7 is a fabric supporting plate 10. Said fabric supporting plate 10 is pivotally mounted at 11 on a bracket 12 which is attached to the bed. This extension 10 extends all the way from the front end of the work support to a point adjacent the front end of the throat plate on the same level as the work support.

This extension has a depressed portion in rear of a line disposed adjacent the front end of the throat plate, and this provides a recess or space for the mounting of a binder.

The binder illustrated in the drawings is shown at 13 and is of the English binder type. In this type of binder, the binding strip which passes through the binder is inverted and then directed about the edges of the fabric section being bound. The binder, therefore, has its longitudinal axis extending at right angles to the line of feed. The binding strip passes through tension posts 14 carried by the bracket 12, and then enters the receiving end 15 of the binder. The binding strip

55

is folded upon itself and then inverted at the inclined portion 16 of the binder, and is then guided in the direction of the feed of the fabric sections. The fabric section being bound passes through the lefthand end of the binder as viewed in Fig. 1, and this is what lays the upper and lower portions of the binding about the edges of the fabric. This extension 10 is held in closed position by a spring latch 17. It may be readily withdrawn and swung about the pivotal support 11 therefor, in order to give access to the parts of the machine therebeneath and also to give more ready access to the binder, if desired. The binder 13 is mounted on the support 18 to which it is secured by screws 19, 19. These screws pass through an elongated slot 20 in the supporting member and serve as a means whereby the binder may be adjusted toward and from the fabric section for causing the binding strip to overlie to a greater or less extent the fabric section being stitched. This supporting member 18 is in turn mounted on a supporting bar 21. The supporting member is provided with vertical slots 22, 22, and screws 23, 23 passing therethrough serve to clamp said member 18 to the bar and permit the member 18 to be raised and lowered and this will raise or lower the binder relative to the plane of the work support. The supporting bar 21 is attached to a bracket 24. This bracket 24 is shown in perspective in Fig. 6. It consists of a vertical portion having horizontal slots 25, 25 therethrough, and screws 26 passing through these slots secure the bracket to the standard 2 of the machine. The bracket has a horizontal portion 24a provided with a longitudinal slot 27. There is a recess 28 at the outer end of the slot which extends around into the vertical portion of the bracket.

Attached to the supporting bar 21 is a plate 29 which fits within the slot 27. This plate is of substantially the same thickness as the horizontal portion 24a of the bracket. Attached to the inner face of the plate 29 is a spring member 30. Said member 30 is rigidly fixed to the plate 29 by means of screws 31. The ends of this spring member 30 are curved outwardly away from the bracket as indicated at 32, 32. This spring member is of sufficient width so that it overlies the sides of the slot 27 and bears against the rear face of this horizontal section 24a of the bracket. The recess 28 is of sufficient height to permit the spring member 30 to pass therethrough, and therefore, the binder may be attached to the bracket by inserting the end 32 of this spring member in the recess 28, and passing the plate 29 into the slot 27. This provides a means whereby the binder is supported so that it may be moved in an end-wise direction. It may be moved to an operative position for guiding a binding strip about the edge of a fabric section, and it also may be retracted and moved to an inoperative position while still supported by the bracket, or it may be disconnected from the bracket. The slots 25 in the bracket permit said bracket to be adjusted toward the front of the machine or toward the rear of the machine, and this enables the delivery end of the binder to be set closer to or further away from the needle.

A latch means is provided for holding the binder in its operative position. This latch means includes a latch 33 which is pivoted at 34 to the supporting bar 21. The latch is provided with a handle member 35 and with a locking nose member 36. The horizontal portion 24a of the bracket 24 is provided with a recess 37. A spring 38 coiled about the supporting screw 39 is attached to an

abutment pin 40. This spring rests against the latch and the end of the spring is seated in a groove in the latch. The spring normally turns the latch in a counter-clockwise direction. When it is desired to release the binder and move it away from its operative position, the operator presses on the handle member 35 so as to move the latch in a clockwise direction. This will lift the nose from the recess 31, and thus release the supporting bar 21 so that it may be moved along the slot 27. There is a stop 33a which limits the movement of the latch on the supporting bar 21. A pressure on the handle member 35 of the latch to the right, as viewed in Fig. 1, which is the necessary pressure to release the latch, will also force the supporting bar to the right and withdraw the binder to an inoperative position. Further movement of the handle member 35 to the right will entirely disconnect the binder from the bracket 24. When it is desired to return the binder to its operative position, the operator may press on the handle member or on the end of the bar 21, and move the binder up to the fabric section. The spring will cause the latch to automatically engage the recess 31 and thus hold the binder in its set operative position.

It is obvious that minor changes in the details of construction and the arrangement of the parts may be made without departing from the spirit of the invention as set forth in the appended 30 claims.

Having thus described the invention, what I claim as new and desire to secure by Letters-Patent is—

Patent, 15
1. In a sewing machine, the combination of 35
a supporting bed, a standard carried thereby, a
work-support spaced from said standard, a binder
for directing a binding strip about the edge of
the fabric section being stitched, means for sup-
porting said binder on said standard whereby 40
the same may be moved to a set operative pos-
ition and to an inoperative position including a
pivotally supported latch engaging the binder sup-
port for holding the binder in a set position, said 45
latch having a handle member disposed so that a
movement thereof in a direction for releasing the
latch will also move said binder away from op-
erative position.

2. In a sewing machine, the combination of a supporting bed, a standard carried thereby, a work support spaced from said standard, a binder for directing a binding strip about the edge of the fabric section being stitched, means for supporting said binder on said standard whereby the same may be moved to a set operative position and to an inoperative position including a pivotally supported latch engaging the binder support for holding the binder in a set position, said latch having a handle member disposed so that a movement thereof in a direction for releasing the latch will also move said binder away from operative position, and a spring means operating on said latch for automatically causing said latch to lock said binder in set operative position. 55 60 65

3. In a sewing machine, the combination of a supporting bed, a standard carried thereby, a work support spaced from said standard, a binder for directing a binding strip about the edge of the fabric section being stitched, a bracket attached to said standard, a supporting bar mounted on said bracket and shiftable in an endwise direction toward and from the work support, said binder being carried by said bar and disposed in the space between the standard and the work 75

- support, and means whereby said binder may be moved to a set operative position and to an in-operative position including a pivotally supported latch engaging the binder support for holding the binder in a set position, said latch having a handle member disposed so that a movement thereof in a direction for releasing the latch will also move said binder away from operative position.
- 5 4. In a sewing machine, the combination of a supporting bed, a standard carried thereby, a work support spaced from said standard, a binder for directing a binding strip about the edge of the fabric section being stitched, a bracket attached to said standard, a supporting bar mounted on said bracket and shiftable in an endwise direction toward and from the work support, said binder being carried by said bar and disposed in the space between the standard and the work support, means whereby said binder may be moved to a set operative position and to an in-operative position including a pivotally supported latch engaging the binder support for holding the binder in a set position, said latch having a handle member disposed so that a movement thereof in a direction for releasing the latch will also move said binder away from operative position, and a spring means operating on said latch for automatically causing said latch to lock said binder in set operative position
- 10 5. In a sewing machine, the combination of a supporting bed, a standard carried thereby, a work support spaced from said standard, a binder for directing a binding strip about the edge of the fabric section being stitched, a supporting bracket for said binder including a vertical portion adapted to be attached to the standard and a horizontal portion formed integral therewith and lying in a line at right angles to the line of feed, a supporting bar mounted on said horizontal portion of the bracket and shiftable endwise thereof, means whereby said binder is supported on said bar, and a latch attached to and moving with said bar, said bracket having a recess adapted to be engaged by said latch for holding the binder in set operative position.
- 15 6. In a sewing machine, the combination of a supporting bed, a standard carried thereby, a work support spaced from said standard, a binder for directing a binding strip about the edge of the fabric section being stitched, a supporting bracket for said binder including a vertical portion adapted to be attached to the standard and a horizontal portion formed integral therewith and lying in a line at right angles to the line of feed, a supporting bar mounted on said horizontal portion of the bracket and shiftable endwise thereof, means whereby said binder is supported on said bar, a latch attached to and moving with said bar, said bracket having a recess adapted to be engaged by said latch for holding the binder in set operative position, said latch having a handle member disposed so that pressure on the handle member will move the latch to release the same will also move the binder away from operative position.
- 20 7. In a sewing machine, the combination of a supporting bed, a standard carried thereby, a work support spaced from said standard, a binder for directing a binding strip about the edge of the fabric section being stitched, a supporting bracket for said binder including a vertical portion adapted to be attached to the standard and a horizontal portion formed integral therewith and lying in a line at right angles to the line of feed, a supporting bar mounted on said horizontal portion of the bracket and shiftable endwise thereof, means whereby said binder is supported on said bar, a latch attached to and moving with said bar, said bracket having a recess adapted to be engaged by said latch for holding the binder in set operative position, said latch having a handle member disposed so that pressure on the handle member will move the latch to release the same will also move the binder away from operative position.
- 25 8. In a sewing machine, the combination of a supporting bed, a standard carried thereby, a work support spaced from said standard, a binder for directing a binding strip about the edge of the fabric section being stitched, a supporting bracket for said binder including a vertical portion attached to said standard, and a horizontal portion formed integral therewith and extending in a direction substantially at right angles to the line of feed, said horizontal section having a slot extending endwise thereof, a recess at the outer end of said slot extending into the vertical portion of the bracket and of greater width than the slot, a supporting bar on which said binder is mounted, a plate attached to said bar and adapted to slide in said slot, said plate being of substantially the same width as the slot and the thickness of the bracket, a spring member attached to said plate at the rear side thereof and overlying and bearing against the bracket along the sides of the slot, said plate being of less width than the recess in the vertical portion of the bracket so as to pass therethrough, and means for holding said bar in a set position on said bracket.
- 30 9. In a sewing machine, the combination of a supporting bed, a standard carried thereby, a work support spaced from said standard, a binder for directing a binding strip about the edge of the fabric section being stitched, a supporting bracket for said binder including a vertical portion attached to said standard and a horizontal portion formed integral therewith and extending in a direction substantially at right angles to the line of feed, said horizontal section having a slot extending endwise thereof, a recess at the outer end of said slot extending into the vertical portion of the bracket and of greater width than the slot, a supporting bar on which said binder is mounted, a plate attached to said bar and adapted to slide in said slot, said plate being of substantially the same width as the slot and the thickness of the bracket, a spring member attached to said plate at the rear side thereof and overlying and bearing against the bracket along the sides of the slot, said plate being of less width than the recess in the vertical portion of the bracket so as to pass therethrough, means for holding said bar in a set position on said bracket, said last-named means including a latch attached to the bar and having a holding nose adapted to engage a recess in the bracket, a spring for turning said latch so as to cause the nose of the latch to automatically engage the recess, a handle carried by said latch, and a stop for limiting the movement of the latch, said handle being disposed so that the pressure thereon for releasing the latch will move the supporting bar so as to withdraw the binder from set operative position.
